Refrigerated serve-over case with product display on two

levels; portions in dotted lines (broken lines) in the drawing

refer to disclaimed parts of the refrigerated sales counter; the

upper display level is very high, at the same height as the

rear work surface in front of which the operator stands; the

upper display level has vertical bulkhead arranged on the

front edge of the shelf and bent towards the operator in its

upper part; the operator can pick up both the products

displayed in the upper level thanks to rear transparent and

sliding doors (in broken lines) and the products in the lower

level through not disclaimed sliding drawers (in broken

lines); the front glass can be lifted up to allow products

loading and internal cleaning of the counter; this is shown by

representation No. 1.7, which is a referential view showing

(Continued)

the use status of the article; the bottom view is omitted since the bottom side of the product cannot be seen easily when the product is in use.
